Inventor,

UNITED STATES PATENT OFFICE.

JOHN A. TOREN, OF CHICAGO, ILLINOIS.

PRINTER'S TIE-UP.

1,096,207.

Specification of Letters Patent. Patented May 12, 1914.

Application filed May 24, 1912. Serial No. 699,373.

To all whom it may concern:

Be it known that I, JOHN A. TOREN, a citizen of the United States, residing at Chicago, in the county of Cook and State of Illinois, have invented certain new and useful Improvements in Printers' Tie-Ups, of which the following is a specification.

My invention relates to printers' tie-ups or composition-holders of that general type which employ a separable rectangular metal frame in lieu of the usual string. Various forms of tie-ups of this general class have heretofore been proposed; but, so far as I am aware, they have been so complicated in structure or so difficult and expensive to manufacture, or so unreliable and impractical in use, that but few, if any, have been favorably received by the printing trade.

Among the salient objects of my invention are, to provide a printer's tie-up or composition-holder which will securely hold the type-page by virtue of a wedging effect inherent in the corner-joints of the tie-up frame when the latter is assembled about the type-page; to provide a construction having the above-mentioned wedging effect which at the same time will offer no interference with the outside pressure of quoins and the like upon the type-page when the latter is being locked up for the foundry or press; to provide a construction which will serve as a safe guide in securing correct and uniform length and width of page; to provide a construction which will make the handling of type-pages much safer and speedier than when handled in the old way by tying up with a string; and, generally, to provide a novel, improved, and simplified tie-up of the character described.

My invention, its mode of use, and the advantages adhering therein, will be readily understood when considered in connection with the accompanying drawings, which show one practical mechanical embodiment of the invention, and in which—

Figure 1 is a plan view of my improved printer's tie-up, showing the same as locked up in a chase. Fig. 2 is an edge view of the upper end frame member or bearer shown in Fig. 1. Fig. 3 is an end elevation of Fig. 2. Fig. 4 is an outer side elevation of the frame member shown in Figs. 2 and 3. Fig. 5 is an edge view of the left-hand side frame member or bearer shown in Fig. 1. Fig. 6 is an inner side elevation of the frame member shown in Fig. 5. Fig. 7 is an edge view

of the right-hand side frame member or bearer shown in Fig. 1. Fig. 8 is an inner side elevation of the frame member shown in Fig. 7. Fig. 9 is a cross-sectional detail on the line 9—9 of Fig. 7. Fig. 10 is a cross-sectional detail on the line 10—10 of Fig. 7. Fig. 11 is an edge view of the lower end frame member or bearer shown in Fig. 1. Fig. 12 is an end elevation of Fig. 11. Fig. 13 is an outer side elevation of the frame member shown in Figs. 11 and 12.

Referring to the drawings, 1 and 2 designate the side frame members, or side bearers, and 3 and 4 the end frame members, or end bearers, of my improved type-page holder or tie-up. In practice the end bearer 4 is at the head of the type-page and the end bearer 3, of course, at the foot. The meeting ends of the bearers are all formed with interfitting rectangular hooks and slots which interlock in such a way as to securely hold all four of the frame members or bearers against outward movement in the plane of the frame, although permitting a limited inward movement for a purpose that will hereafter appear; and three of the four joints are so formed as to produce an inward wedging action of the bearers 2 and 3 as the latter are put in place in assembling the frame around a type-page.

Referring more particularly to the specific formation of the corner joints of the frame, the lower end of the side bearer 1 is formed with a plain rectangular slot 5 and hook 6 which snugly interfit with a hook 7 and slot 8 on the left-hand end of the end bearer 4. The upper end of the side bearer 1 is formed with a rectangular slot 9 and hook 10, the free edge 11 of the hook 10 being slightly inclined or wedge-shaped, as clearly shown in Fig. 6, so that the hook is slightly wider on the lower side of the bearer than on the upper. The co-operating end of the end bearer 3 is formed with a slot 12 to receive the free end portion of the hook 10 and with a hook 13 that engages the L-shaped slot 9 of the side bearer 1. The free edge 14 of the hook 13 is also slightly inclined or wedge-shaped, said hook being slightly wider on the upper side of the bearer than on the lower. The right-hand end of the bearer 3 is formed with a slot 15 somewhat wider than slot 12 at the opposite end, and with a hook member 16; and the upper end of the side bearer 2 is formed with a slot 17 somewhat wider than the corresponding slot

9 of the side bearer 1, and with a hook 18. Slot 15 and hook 16 of the end bearer 3 engage the hook 18 and the slot 17 of the side bearer 2; and the free edges 19 and 20 of 5 the hooks 16 and 18 are slightly inclined or wedge-shaped, similar to the inclined free edges 14 and 11 of the hooks 13 and 10, respectively. Furthermore, the opposed inner faces 21 and 22 of the end members of the 10 hooks 16 and 18 are likewise inclined or wedge-shaped, as clearly shown in Figs. 4 and 9. The lower end of the side bearer 2 is formed with a slot 23 and a hook 24 that coöperate, respectively, with a hook 25 and 15 a slot 26 on the right-hand end of the bearer 4. The opposed inner faces 27 and 28 of the end portions of the hooks 24 and 25 are inclined or wedge-shaped, as clearly shown in Figs. 10 and 13.

20 In building up a type-page on a galley, the side and end bearers 1 and 4 are first assembled; and after the type-page is completed, the complementary side and end bearers 2 and 3 are applied in the order named. It will be noted that the described 25 inclined or wedge formations at the joints between the bearers 1 and 3, 3 and 2, and 2 and 4, cause an inward movement of the bearers 2 and 3, the side bearer 2 tending to 30 wedge toward the opposite bearer 1, and end bearer 3 tending to wedge toward the opposite end bearer 4. This causes the frame or tie-up to tightly bind or clamp the type-page, dispensing with the necessity of 35 filling or wedging in between the margins of the type-page and the bearers. It will also be noted that the transverse portions of the slots 9 and 17 of the side bearers 1 and 2 are somewhat wider than the portions of 40 the hooks 13 and 16 engaging the same; also that the slots 15 and 26 of the end bearers 3 and 4 and the longitudinal portions of the slots 17 and 23 of the side bearer 2 are somewhat wider than the portions of the hooks 45 engaged thereby. The result of this is that the side and end bearers 2 and 3, after the tie-up has been assembled around a type-page, are still free to be forced farther inwardly by the quoins 29, when locked up in 50 a chase 30, as shown in Fig. 1.

From the foregoing it will be seen that my improved tie-up constitutes not only a bounding frame or holder for the type-page, but also, when fully assembled around the 55 type-page, serves to bind or clamp the latter, dispensing with the necessity of inserting thin strips of furniture in order to obtain a sufficiently tight engagement between the type-page and the tie-up to prevent danger 60 of parts of the former being pulled out by suction of the inking roller during the process of taking proofs. At the same time, the tie-up frame does not in the least interfere with a further clamping and tightening of 65 the type-page through the action of the

quoins when locked up in the chase, in which latter situation the frame bars or bearers serve the purpose of the furniture usually employed.

The device saves much time by dispensing 70 with the use of the usual tie-up string, insures uniformity in the length and width of the type-pages owing to the fixed dimensions of the bearers or frame bars, and can be left around the type and locked up in the 75 form whenever the margins will allow. The bottom bearer and the right-hand side bearer can be used as a foot and side stick, respectively, by placing a reglet or strip of cardboard between these parts and the quoins. 80

I claim—

1. A printer's tie-up, comprising a rectangular frame made up of straight side and end frame bars formed with interlocking hooks and slots at their ends adapted to be 85 engaged and separated by a relative movement in a direction substantially normal to the plane of the frame, the coöperating hooks of one side frame bar and one end frame bar having engaging surfaces formed 90 wholly in planes perpendicular to the plane of the frame; and the hooks of the other of said end frame bars and the hooks of said side frame bars coöperating therewith being formed with surfaces slightly inclined 95 from a plane perpendicular to the plane of the frame whereby, as said last-named end frame bar is interlocked with the side frame bars, it is bodily wedged laterally in a direction inwardly of the frame. 100

2. A printer's tie-up, comprising a rectangular frame made up of straight side and end frame bars formed with interlocking hooks and slots at their ends adapted to be 105 engaged and separated by a relative movement in a direction substantially normal to the plane of the frame, the coöperating hooks of one side frame bar and one end frame bar having engaging surfaces formed 110 wholly in planes perpendicular to the plane of the frame; and the hooks of the other of said side frame bars and the hooks of said end frame bars coöperating therewith being 115 formed with surfaces slightly inclined from a plane perpendicular to the plane of the frame whereby, as said last-named side frame bar is interlocked with the end frame bars, it is bodily wedged laterally in a direction inwardly of the frame.

3. A printer's tie-up, comprising a rectangular frame made up of straight side and end frame bars formed with interlocking rectangular hooks and slots adapted to be 120 engaged and separated by a relative movement in a direction substantially normal to the plane of the frame, the coöperating hooks at three of the corner joints of the frame being formed with inclined or wedge-shaped surfaces so disposed as to cause a 125 relative inward movement of one of the end 130

frame bars and one of the side frame bars as the latter are interlocked with the complementary side and end frame bars and with each other.

- 5 4. A printer's tie-up, comprising a rectangular frame made up of straight side and end frame bars formed with interlocking rectangular hooks and slots adapted to be engaged and separated by a relative movement in a direction substantially normal to the plane of the frame, the coöperating hooks at three of the corner joints of the frame being formed with inclined or wedge-shaped surfaces so disposed as to cause a

relative inward movement of one of the end frame bars and one of the side frame bars as the latter are interlocked with the complementary side and end frame bars and with each other, and the slots at said three corner joints of the frame having excess width permitting a further bodily inward movement of said inwardly movable end and side bars when said tie-up frame is locked up in a chase or form.
